Donald L. Spender, Waterbury, Conn., assign-ors to Scovill Manufacturing Company, Waterbury, Conn., a corporation of Connecticut

Application October 2, 1936, Serial No. 65,138

Term of patent 14 years

To all whom it may concern:

Be it known that we, William R. Westfall and Donald L. Spender, citizens of the United States of America, residing at Kew Gardens, Long Island, and Waterbury, in the counties of Queens and New Haven and States of New York and Connecticut, respectively, have invented a new, original,
and ornamental Design for Flashlight Casings, of which the following is a specification, reference being had to the accompanying drawing, forming a part thereof.

Fig. 1 is a side view of a flashlight casing, embodying our new design.

Fig. 2 is a front end view of the same.

Fig. 3 is a rear end view of the same.

We claim:

The ornamental design for a flashlight casing
substantially as shown.

DONALD L. SPENDER.
WILLIAM R. WESTFALL.
